UNITED STATES PATENT OFFICE.

HERBERT G. GRANT, OF ATTLEBORO, MASSACHUSETTS, ASSIGNOR TO S. O. BIGNEY & COMPANY, OF ATTLEBORO, MASSACHUSETTS, A CORPORATION OF MASSACHUSETTS.

PROCESS OF TREATING METAL SURFACES.

No Drawing.

Application filed May 20, 1921. Serial No. 471,192.

To all whom it may concern:

Be it known that I, HERBERT G. GRANT, a citizen of the United States, residing at Attleboro, in the county of Bristol and State 5 of Massachusetts, have invented certain new and useful Improvements in Processes of Treating Metal Surfaces, of which the following is a specification.

This invention relates to a new and improved process for producing highly ornamental effects on metal surfaces, such effects as to resemble ribbed-silk in colors, oriental or Persian effects, or other desired effects produced by various combinations of colors 10 upon such metal surfaces; and the object of the invention is to produce these different ornamental effects by depositing gold or other metals of different colors in different layers to produce various combinations and 15 then subject the surface so treated to a process of forcing portions of the colored patterns below their normal surface, or by raising a multiplicity of protecting ribs through such surface, which effects in some cases may 20 be produced by a so-called engine turning 25 operation thereby adding to the highly ornamental effects on the metal and at the same time protecting the deposited colors rendering the surfaces so treated very durable 30 as these raised ribs serve to effectually protect the depressed colored portions thereof.

It is well known in the art that fine gold may be produced in addition to its natural 35 color, in a limited number of other distinct colors such as red, white, and green, and I have found that these colors may be deposited electrically in different layers onto the surface of metal to produce highly ornamental and effective designs, and the following is a detailed description of one method by which my improved result may be produced.

I first deposit either electrically or otherwise 45 upon a metal surface a layer of gold of a certain color; I then deposit a protecting covering upon that portion of the first colored layer which is to be preserved as a part of the design when the article is completed, which covering prevents the color 50 from taking on other colors during subsequent depositing operations. I next deposit another color over the surface to be treated.

I then deposit a protecting material over that portion of the second color which is to be preserved in the design. I then deposit a third color over the surface to be treated. I finally remove the protecting material from all of those portions which were covered with the same, exposing the various 60 previously protected colors of the design.

I do not limit myself to the employment of just the limited number of colors above enumerated as still other colors may be deposited and covered with a protecting material in the manner described without departing from the spirit and scope of my invention.

After depositing all or any of these colors in the manner above described to produce 70 the desired design and ornamental effect I next subject the surface to another step in the process by which parts of the colored portions of the surface are depressed below their normal plane or below adjacent parts 75 thereof. In other words a multiplicity of protecting ribs are raised through the treated surface, which results may be accomplished by what is known as an engine-turning process or operation, which operation 80 serves to iron, press or force portions of the colored surface into narrowly spaced apart grooves below their normal level thereby effectually preserving the design of colors as they are depressed below the wearing surface 85 of the resulting raised portions or ribs, rendering the design produced by my process very durable and practically indestructible.

I have described the depositing of gold 90 of various colors, but I do not wish to be restricted to the use of gold alone as other metals of different colors may be employed in my new and improved process in which a great variety of effects may be produced by 95 alternately depositing layers of different colors and between which layers I deposit a protecting material over those portions of the different colors to be preserved in the design after which I remove the protecting material and treat the colored surface to an engine-turning operation.

My improved process is extremely simple and practical and by its use highly-ornamental surfaces of appropriate designs may 105 be produced on many articles of jewelry as

well as on watch cases, cigarette cases, vanity cases and a great variety of other articles rendering them highly ornamental.

I claim:

- 5 An improved method of producing an ornamental effect on metal surfaces, which consists in electrically depositing a plurality of layers of metal films upon a metal plate, covering that portion of said plate with a 10 protecting material between each two ap-

plications of metal films which is to be preserved in the design, subsequently removing the protecting material and forcing or pressing portions of the layers below their normal or deposited surfaces and raising protecting portions of metal between said depressed portions. 15

In testimony whereof I affix my signature.

HERBERT G. GRANT.
